UNITED STATES PATENT OFFICE

FRED HIMMEL AND ISIDORE HIMMEL, OF NEW HAVEN, CONNECTICUT, ASSIGNORS TO THE HIMMEL BROTHERS COMPANY, OF NEW HAVEN, CONNECTICUT, A CORPORA-TION

DESIGN FOR A DOOR FOR SHOWER-BATH CABINETS

Application filed December 4, 1930. Serial No. 37,887. Term of patent 14 years.

To all whom it may concern:

Be it known that we, FRED HIMMEL and ISIDORE HIMMEL, citizens of the United States, residing at New Haven, in the county of New Haven and State of Connecticut, have invented a new, original, and ornamental Design for a Door for Shower-Bath Cabinets, of which the following is a specification, reference being had to the accompanying drawing, forming part thereof.

Fig. 1 is a face view of a door for shower-bath cabinets showing our new design;

Fig. 2 is a face view of one corner on an enlarged scale, and

Fig. 3 is an end view of the door.

We claim:

The ornamental design for a door for shower-bath cabinets as shown.

FRED HIMMEL.
ISIDORE HIMMEL.
